BY *Coward L. Nelson*
ATTORNEY.

UNITED STATES PATENT OFFICE.

HERMAN C. PAGE, OF NEWARK, NEW JERSEY, ASSIGNOR TO THE WHITEHEAD & HOAG COMPANY, OF NEWARK, NEW JERSEY, A CORPORATION OF NEW JERSEY.

MEANS FOR ATTACHING NAME-PLATES.

1,275,172.

Specification of Letters Patent. Patented Aug. 6, 1918.

Application filed August 22, 1917. Serial No. 187,621.

To all whom it may concern:

Be it known that I, HERMAN C. PAGE, a citizen of the United States of America, and resident of Newark, in the county of Essex, 5 in the State of New Jersey, have invented new and useful Improvements in Means for Attaching Name-Plates, of which the following, taken in connection with the accompanying drawings, is a full, clear, and exact 10 description.

This invention relates to certain improvements in means for attaching name-plates to automobile radiators and other objects to which it might be desirable to apply a plate 15 of this character.

These plates are usually made in disk form with more or less elaborate finish on the front face and are adapted to be applied to the upper front portion of the radiator plate 20 which is also finished more or less elaborately by varnish, nickel or enamel, and the main object of my present invention is to provide simple means whereby a plate of 25 this character may be easily and quickly secured to its supporting plate without mutilating the finish of either plate, and at the same time to conceal the locking means when the name-plate is adjusted for use, thereby reducing to a minimum the liability of 30 malicious removal, and presenting the appearance of unity of the two plates.

Another object is to bring the plates into interlocking engagement with a sliding, wedging action and to hold them in operative relation by means of a spring catch and limiting stops, whereby the name-plate will be firmly held against rattling or accidental displacement.

Other objects and uses relating to specific 40 parts of the device will be brought out in the following description.

In the drawings—

Figure 1 is a front elevation of the upper portion of an automobile radiator showing 45 a name-plate attached thereto by my improved connection.

Fig. 2 is an enlarged rear face view of a portion of the supporting plate and means for attaching the name-plate thereto in its 50 initial position of just entering the opening in the supporting plate, but not interlocked therewith.

Fig. 3 is a view similar to Fig. 2 with the parts in interlocked position ready for use.

55 Figs. 4 and 5 are detail sectional views

taken, respectively, on lines 4—4 and 5—5, Fig. 3.

In order that my invention may be clearly understood, I have shown a portion of an automobile radiator —1— as provided with 60 a marginal cover-plate —2— extending across the upper front portion of the radiator where the name-plate is usually affixed, the plate —2— being provided at or near its center with a T-shape opening —3— having 65 a central, upwardly-extending branch opening —4— communicating with the main opening.

For convenience of description, the lower portion of the opening may be termed the 70 stem, the laterally extending portions, the side branches, and the upper portion —4—, the top branch, although it will be understood that I do not limit myself to the precise form of the opening as herein shown 75 and described.

The name-plate, as —A—, which is to be attached to the front plate —2— of the radiator consists, in this instance, of a substantially flat, circular disk, the front face of 80 which may be embossed or finished in any artistic manner desired, while the back thereof is provided with a device adapted to cooperate with the opening and walls thereof 85 for securement of the name-plate to the supporting plate.

This device on the back of the name-plate is also somewhat T-shape in elevation, the base or stem, as —5—, of which is of substantially the same width as the corresponding 90 base or stem of the opening, while the intermediate portion is provided with a pair of laterally projecting wings —6— of slightly less vertical width than the corresponding branches of the opening —3—, the distance 95 across said wings laterally from end to end being slightly less than the width of the opening across its branches, thus permitting the base and wings on the back of the name-plate to readily pass through the corresponding 100 portions of the opening —3— in the supporting plate —2—.

The distance from the lower edge of the base —5— to the upper edges of the wings —6— is considerably less than the distance 105 from the base of the opening to the lower edges of the lateral branches of said opening so that when the base and wings of the name-plate are passed from the front rearwardly through said opening, the wings —6— may 110

be moved downwardly with the name-plate into interlocking engagement with the adjacent walls of the opening below the lateral branches thereof.

- 5 The front faces of the lower portions of the free ends of the wings —6— are preferably beveled rearwardly and downwardly so that when the wings are passed through the lateral branches of the opening —3— 10 and moved downwardly, they will wedge against the rear faces of opposite walls of the opening below the lateral branches thereof to firmly hold the name-plate against rattling when adjusted for use, at 15 which time the base portion —5— of the locking device on the name-plate will be engaged with the lower edge of the opening —3— to hold the name-plate against further downward movement.
- 20 This base portion —5— is also provided with rearwardly projecting flanges —7— at its opposite upright edges which engage the corresponding walls of the opening to hold a name-plate against lateral displacement in 25 either direction.

The locking device on the back of the name-plate is also provided with a spring tongue —8— projecting upwardly from its upper edge and is of slightly less size than 30 that of the upwardly extending branch —4— of the opening —3— so as to readily enter said opening when the wings —6— are slidably interlocked with the adjacent walls of said opening, the tongue —8— 35 being tensioned to snap rearwardly into the branch —4— to interlock with the upper wall of said branch when the name plate is adjusted for use.

The wings —6— are also under spring 40 tension when wedged downwardly against the rear faces of the adjacent walls of the opening, as shown more clearly in Figs. 3 and 5, the lower, outer edges of the wings being deflected rearwardly so as to produce 45 the bevel faces previously mentioned for wedging coaction with the walls of the opening to yieldingly hold the name-plate against forward displacement and also against rattling.

50 The name-plate and also its supporting plate are preferably made of relatively thin sheet metal which is also more or less yielding so that in case it is necessary to remove the name-plate, the upper edge of the latter 55 may be sprung forwardly sufficiently to withdraw the tongue —8— from interlocking engagement with the upper wall of the branch —4— of the opening —3—, whereupon the name-plate may be moved upwardly to withdraw the wings —6— from 60 interlocking engagement with the walls of the opening —3— into registration with the lateral branches of said opening, whereupon the plate may be withdrawn forwardly from 65 its supporting plate.

It will be noted, however, that the entire locking device is wholly within the area of the name-plate and centrally thereof so that when said plate is adjusted for use upon its supporting plate, the locking means 70 is wholly concealed by the name-plate and that owing to the slight movement necessary to bring the name-plate to its locked position, the liability of marring the finished surface of the supporting plate is reduced 75 to a minimum.

What I claim is:

1. The combination of a name-plate and a supporting plate therefor, said plates having detachable interlocking connections at 80 the back and wholly within the area of the name-plate, said connections including a pair of wings on the name-plate passed through an opening in the supporting plate and interlocked with the walls of said opening by 85 sliding engagement in one direction, and a spring catch also on the name plate and tensioned to spring into engagement with one of the walls of the opening when the wings are moved to their locking positions 90 to hold the name-plate against movement in a reverse direction.

2. The combination with a support having a T-shaped opening formed with a central branch, of a plate having a T-shaped 95 frame secured thereto and adapted to be passed through the T-shaped opening and interlocked with the wall of said opening by sliding engagement in one direction, and a catch adapted to engage the wall of the 100 central branch when said sliding engagement has been effected.

3. The combination of a supporting plate having an opening therethrough, and a name-plate having beveled wings on its back 105 passed through said opening and its beveled portions wedgingly interlocked with the walls of said opening by sliding movement in one direction, said name-plate having a spring tongue tensioned to spring into said 110 opening when the wings are interlocked with the supporting plate.

4. The combination with a support having a T-shaped opening formed with a central branch, of a plate having a T-shaped frame 115 secured thereto and adapted to be passed through the T-shaped opening and interlocked with the wall of said opening by sliding engagement in one direction, and a pair of flanges on the frame extending substantially perpendicular to the plate and adapted for contact with walls of said opening.

5. In a device of the class described, a plate, a frame secured thereto and comprising a pair of oppositely extending wings spaced from, but lying substantially parallel with the plate, a pair of flanges extending at substantially right angles to the wings, and a catch positioned upon the side 125 130

or said wings opposite that upon which said flanges are located.

6. In a device of the class described, a name-plate, a frame secured thereto and comprising a body portion formed with oppositely extending offset wings having end portions spaced from, but lying substantially parallel with, the plate, said body portion having a pair of spaced flanges extending at substantially right angles to the

plate, and a catch extending from the body portion upon the side of the wings opposite that upon which said flanges are disposed.

In witness whereof I have hereunto set 15
my hand this 15th day of August, 1917.

HERMAN C. PAGE.
